GEORGE A. GAUTHIER, OF HARTFORD, CONNECTICUT, ASSIGNOR TO THE ARROW ELECTRIC COMPANY, OF HARTFORD, CONNECTICUT, A CORPORATION OF CONNECTICUT.

ATTACHMENT-PLUG RECEPTACLE.

1,159,207.

Specification of Letters Patent.

Patented Nov. 2, 1915.

Application filed May 22, 1915. Serial No. 29,756.

To all whom it may concern:

Be it known that I, GEORGE A. GAUTHIER, a citizen of the United States of America, and residing at Hartford, in the county of 5 Hartford and State of Connecticut, have invented a certain new and Improved Attachment-Plug Receptacle, of which the following is a specification.

My invention relates to attachment plug 10 receptacles and particularly to a shutter mechanism for the plugging apertures of the receptacle, the object of my invention being to provide a simple and efficient mechanism for closing these apertures against the 15 entry of dust and dirt when the plug is not inserted.

In the accompanying drawings, Figure 1 is a broken plan of a receptacle in which my 20 invention is embodied in one form; Fig. 2 is a vertical section therethrough; Fig. 3 is a plan with the upper button removed but showing the shutter spindle in section; Fig. 4 is a diagrammatic section showing in three 25 positions the operation of the shutter spring drawn to a larger scale; Fig. 5 is a perspective of the shutter; and Fig. 6 is a perspective of an attachment adapted to cooperate with the receptacle shown in Figs. 1 to 3.

In the embodiment of my invention here 30 illustrated, the present receptacle comprises an insulating body 10 having at its opposite ends upstanding ledges 11 on which rest the yoke straps 12 secured by the screws 13 and by means of which the receptacle is 35 supported in an outlet box of usual form (not shown) and to which the cover plate 14 is attached by means of screws 15. On the upper face of the insulating body and on the longitudinal axis thereof are spaced 40 apart the jack-receiving spring terminals 16 and 17 respectively connected by straps 18 and 19 to the respective binding screws 20 and 21. A block 22 of insulation, fitting between the ledges 11 and substantially flush 45 with the upper faces of the latter, is pierced by holes 23 and 24 into which the terminals 16 and 17 extend, thus forming separate insulated chambers therefor.

The cover plate 14 overlying the receptacle is provided with a circular aperture 25 embracing within its area the perforations 23 and 24 of the block 22. Fitting freely within this aperture is arranged a disk 26, preferably of insulation, mounted on a spindle 50 the axis of which passes through a

plane connecting the terminals 16 and 17 at a point mid-way between the latter. This disk is pierced by perforations 28 and 29 which, in predetermined position of the disk register with the holes 23 and 24 of the block 60 22, thus permitting the jacks 30 and 31 of the attachment plug 32 to enter the latter and engage the receptacle terminals 16 and 17 situated therein. Under normal conditions however the disk 26 takes a position 65 such that the plane of its apertures 28 and 29 is at right angles to the plane of the holes 23 and 24 in the block 22, thus closing the latter. The means employed to effect this movement of the disk comprises, in the 70 particular embodiment of my invention here shown, a coil spring 33 on the spindle 27, the opposite ends 34, 35 of which engage on opposite sides of and extend beyond the bridge piece 36 fast on the spindle and into 75 engagement with the opposite sides of a rib 37 projecting into the well 38 in the body 10 through which, as well as through the block 22, the spindle 27 passes. A washer 39 engages the lower end of the spindle and 80 thus holds the disk against longitudinal displacement while at the same time permitting its free rotary motion.

The operation of the shutter mechanism is 85 readily understood.

When it is desired to insert the attachment plug 32, the jacks 30 and 31 are brought into engagement with the apertures 28 and 29 in the disk and the latter then rotated in either direction on its axis 27 until 90 the apertures register with the holes 23, 24, in the block 22. The jacks 30 and 31 may then be pushed home into engagement with the terminals 16 and 17 therein. In this position the shutter spring 33 has been tensioned since in whichever direction it is rotated, one or the other of the spring ends 34, 35, remains in engagement with the rib 37, while the other spring end has been carried through an arc of 90° by reason of its engagement with the bridge piece 36 which is fast on the spindle 27. Obviously when the plug is removed, either intentionally or accidentally, the spring 33 at once returns the shutter disk 26 to its normal position in 100 which the holes 23, 24 of the block 22 of the receptacle are obstructed.

One obvious advantage of the shutter mechanism described lies in the fact that the receptacle terminals 16 and 17 may be 110

placed very close to the surface of the receptacle, thus enabling short jacks of the type illustrated in Fig. 6, to be employed. These jacks are so short and of such construction that the plug may be tipped out of the receptacle at substantially any angle and it is not necessary, in order to detach the plug, that it be drawn straight out of the receptacle as is the case in the usual receptacle constructions in which a shutter mechanism is employed to obstruct the plugging aperture.

Various changes in detail and modifications of the present construction will readily suggest themselves to those skilled in the art without departing from what I claim as my invention.

I claim as my invention:—

1. An attachment plug receptacle, having a pair of receiving terminals, a rotary shutter common thereto and having a pair of apertures normally out of register therewith but moving into registry on the rotation of said shutter to permit the jacks of an attachment plug to pass through said shutter into engagement with said receiving terminals.

2. An attachment plug receptacle, having a pair of receiving terminals, a rotary shutter common thereto and having a pair of apertures normally out of register therewith but moving into registry on the rotation of said shutter to permit the jacks of an attachment plug to pass through said shutter into engagement with said receiving terminals, in combination with means to restore said shutter to normal out-of-registry position on the withdrawal of the plug jacks.

3. An attachment plug receptacle, having a pair of receiving terminals, a rotary shutter common thereto and having a pair of apertures normally out of register therewith but moving into registry on the rotation of said shutter to permit the jacks of an attachment plug to pass through said shutter into engagement with said receiving terminals, in combination with spring means to restore said shutter to normal out-of-registry position on the withdrawal of the plug jacks.

4. An attachment plug receptacle having a pair of receiving terminals, a cover plate having an aperture embracing said terminals within its area, a rotary shutter arranged in said aperture and having a pair of apertures normally out of register with said terminals but moving into registry therewith on the rotation of said shutter to permit the jacks of an attachment plug to pass through the shutter into engagement with the receiving terminals.

5. An attachment plug receptacle having a pair of receiving terminals, a cover plate having an aperture embracing said terminals within its area, a rotary shutter arranged in said aperture substantially flush at its outer

face with the outer face of the cover plate, and having a pair of apertures normally out of register with said terminals but moving into registry therewith on the rotation of said shutter to prevent the jacks of an attachment plug to pass through the shutter into engagement with the receiving terminals.

6. An attachment plug receptacle having a pair of receiving terminals, a rotary shutter common thereto and having free-ways therethrough adapted to register with said terminals to admit thereto through the shutter the jacks of an attachment plug and means obstructing said free-ways when the shutter is out of register with the receptacle terminals.

7. An attachment plug receptacle having a pair of receiving terminals, a rotary shutter common thereto and having free-ways therethrough adapted to register with said terminals to admit thereto through the shutter the jacks of an attachment plug and insulation overlaid by said shutter and obstructing its free-ways when it is out of register with the receptacle terminals.

8. An attachment plug receptacle comprising an insulating body having wells and receiving terminals therein, a rotary shutter having free-ways adapted to register with said wells to admit the jacks of an attachment plug, said shutter normally taking a position in which its free-ways are obstructed by the body of the receptacle.

9. In an attachment plug receptacle, receiving terminals, a rotary shutter normally blocking access thereto but having apertures registering therewith on the rotation of the shutter, a spring operatively engaging said shutter and the body of the receptacle and normally holding the shutter with its free-ways out of register with the receiving terminals.

10. In an attachment plug receptacle, receiving terminals, a rotary shutter rotatable in either direction on its axis and normally blocking access to the said terminals, said shutter having free-ways adapted to be brought into register with said terminals on the rotation of the shutter and through which the jacks of an attachment plug may be passed into engagement with the said terminals.

11. In an attachment plug receptacle, receiving terminals, a rotary shutter rotatable in either direction on its axis and normally blocking access to the said terminals, said shutter having free-ways adapted to be brought into register with said terminals on the rotation of the shutter and through which the jacks of an attachment plug may be passed into engagement with the said terminals, in combination with spring means for holding said shutter normally in position to block access to said terminals.

12. In an attachment plug receptacle, a

pair of receiving terminals, a shutter having free-ways but normally blocking access to said terminals, a coil spring, a member rigid with the shutter freely engaged between the 5 opposite ends of said spring, and an abutment on the receptacle body also freely engaged between the ends of said spring, whereby the shutter is returned to its normal obstructing position after its rotation 10 in either direction.

13. In an attachment plug receptacle, a pair of receiving terminals, a shutter having free-ways but normally blocking access to said terminals, a coil spring, a spindle 15 rigid with the shutter and passing through said spring, a bridge piece on said spindle engaged between the ends of said coil spring, a well in the receptacle body in which said bridge piece lies and a rib extending into 20 said well and engaged between the ends of said coil spring, for the purpose described.

14. In an attachment plug receptacle, a shutter comprising an apertured disk, a spindle rigid therewith, a coil spring on said 25 spindle, and a bridge piece engaged between the opposite ends of said coil spring.

15. In an attachment plug receptacle, an insulating body, plug receiving terminals

carried thereby, a shutter normally obstructing access to said terminals, a spindle 30 rigid with said shutter, piercing the receptacle body and secured beneath the same against longitudinal displacement, and spring means on said spindle for normally maintaining the same in obstructing position. 35

16. In an attachment plug, a two-piece insulating body, comprising a base, plug-receiving terminals carried thereby, and a block overlying said base and pierced to form independent terminal chambers, in 40 combination with a rotary shutter overlying said block and apertured to form free-ways adapted to be brought into register with said terminals, and means to normally maintain said free-ways out of register with 45 said receiving terminals whereby access to the latter is blocked by the body of the shutter.

In testimony whereof I have signed my name to this specification, in the presence of 50 two subscribing witnesses.
